UNITED STATES PATENT OFFICE.

WILLIAM A. REICH, OF ESTHerville, IOWA.

AUTO TAIL-LIGHT.

1,279,003.

Specification of Letters Patent. Patented Sept. 17, 1918.

Application filed August 17, 1917. Serial No. 186,748.

To all whom it may concern:

Be it known that I, WILLIAM A. REICH, a citizen of the United States, residing at Estherville, in the county of Emmet and State of Iowa, have invented certain new and useful Improvements in Auto Tail-Lights, of which the following is a specification.

This invention relates to a combination license tag holder and tail lamp for automobiles, and it is a purpose of my invention to provide a structure of this character which can be used by day to display an ordinary license tag, and which has the parts thereof so arranged that by slight readjustment of parts a tail lamp is provided which gives the required red warning light on the rear of the machine, and at the same time shows an illuminated number corresponding to the number of the license tag.

A further object lies in so constructing the parts that a license tag, as well as the number to be illuminated, can be readily fitted in the proper position for use, and can be as easily removed and replaced by other numbers and tags.

Yet another object is to provide structure in which a neat and attractive appearing holder and light is provided, and with which the setting to show the license tag or to show the illuminated numbers will be positively maintained.

With the above and other objects in view, which will be in part described and in part understood from the specification, drawing, and claims, my invention consists in certain novel features of construction and combination of parts which will be hereinafter more fully set forth.

40 In the drawings:—

Figure 1 is a view in elevation of the device of my invention showing the parts adjusted to the position which they would occupy when used as a tail light;

45 Fig. 2 is a view in end elevation of the disclosure of Fig. 1;

Fig. 3 is a transverse vertical sectional view taken on the line 3—3 of Fig. 1; and

50 Fig. 4 is a view in elevation of the case taken substantially at the opposite side from the showing of Fig. 1.

The main case of the device is made of such form that in cross section it takes substantially the shape of an equilateral triangle, the sides 1 and 2 being made solid and having the end 3 connected therewith, and the end 4 being made separate from the main body portion to be removably fitted thereon and held in place by the use of bolts or screws 5. The forward edges of the sides 1 and 2 of the body portion are turned down to provide flanges 6 and 7, which form substantially slides at the forward side of the casing and at top and bottom of a sight opening provided on the remaining side of the triangular body. Bearing-trunnions 8 and 9 are provided on the ends 3 and 4 of the body, and the trunnion 9 preferably has a body portion 10 which is shaped to present substantially a triangular form, as is better shown in Fig. 2.

Brackets 11 and 12 are provided with the bearings 13 and 14, and the casing is mounted with the trunnions 8 and 9 thereof fitted to these bearings 13 and 14, so that as the brackets 11 and 12 are mounted upon an automobile or other vehicle, the casing will be held spaced from the body or other portion to which attachment is made. A spring 15 is carried by the bracket member 12, in the bearing 14 of which the trunnion 9 is mounted, and this spring 15, which is intended to act as a retaining spring, bears against the sides of the triangular body 10 of the trunnion 9, substantially after the manner shown in Fig. 2, so that as the casing is turned to different adjustments, it will be always retained in such a relation that one of the flat sides thereof is presented outwardly. Also, when the casing is adjusted the retaining spring 15 will act to hold the same against casual or accidental readjustment.

The side 1, of the casing, is made flat on its outer face to receive a license number, tag or plate 16, and screws or bolts 17 are provided to retain the same in a seated position. The side 2 of the casing has electric base sockets 17 and 18 mounted therein, and electric lamp bulbs 19 when mounted in these base sockets will be within the casing and so disposed that the light rays therefrom will

shine through the openings between the flanges or bent in edges 6 and 7. As has been stated, it is one of the purposes of my invention to provide a tail lamp which will not only show the warning light, but will 5 show an illuminated number, and with this purpose in view I provide a cut-out stencil 10 which is of such size that it will fit within the opening of the casing and will be held 15 in place by being received in the guide ways back of the flanges or edges 6 and 7, a sheet of red celluloid, or other suitable transparent material being mounted on the inner side of the stencil member 20, substantially as shown at 21. A glass, or other transparent member, 22 is mounted on the forward side of the stencil member and as these various 20 portions 20, 21, and 22, are fitted to be held against inward displacement by bearing 25 against the forward edges of the walls 1 and 2, and against outward displacement by the edges 6 and 7 of these walls, the fitting of the end member 4 in place will mount the several members to be held within the opening 30 of the casing and to be retained against displacement or shifting. As the stencil member has the numbers cut out therefrom and the colored sheet of material is placed entirely over the stencil, the light cast through 35 the stencil openings from the lamps 19 will show red. Suitable circuit connections will be made in the wires 23 of the base sockets 17 and 18, and electric current for the lamps 19 will be supplied and controlled in any desired way.

In the use of the device, the supporting bracket members 11 and 12 will be fitted upon the body or upon other portions of the vehicle, at the rear, and after the case has 40 been mounted in place the circuit connections are established. When the case is swung to such a position that the license tag 16 thereof shows from the rear, the spring 15 will bear against the body 10 of the trunnion 9, and in consequence the casing will be 45 held against turning in either direction to become displaced from this setting. This display of the license tag will be proper for daylight operation of the machine, and in fact a standard license tag such as is issued 50 by States, and other licensing bodies, can be used, in this way making it possible to display the standard and authorized license tag. The stencil member 20 will be cut to 55 show the same numbers as are contained on the license tag or plate, and in night operation of the machine, the casing will be shifted so that the side having the glass 22 fitted thereto will be presented rearwardly, and 60 then when the current is switched on to the lights 19, the rays from the light will be passed through the sheet 21 and consequently will show red through the cut out of the stencil member 20. In this way, not

only will a lawful display of the red tail 65 light be accomplished but an illuminated number will be shown, and the license number of the vehicle will thus be more readily discernible.

From the foregoing it will be seen that I 70 have provided a combination license display and tail lamp which is of such character that it will conform in all respects to varied laws of different localities, which will make driving more safe by positively identifying 75 danger signals as being upon vehicles and distinguishing the same from red lanterns placed at excavations and the like; and, which will at the same time make it possible to readily, and with facility, discern and 80 make out the license numbers of a vehicle.

While in the foregoing I have shown and described only one exact construction of the parts and have set forth but one manner of assembling the same, it will be apparent that 85 changes and variations might be resorted to, in view of which fact I wish to be limited only to such points as may be set forth in the claims.

I claim:—

1. A combined license display and tail lamp including a substantially triangular casing having bearing trunnions at the ends thereof, bearing brackets in which said casing is mounted to be capable of revoluble 95 movement and said bearing brackets adapted to be mounted upon the rear of the vehicle, one of the sides of the casing being formed to receive a standard license tag and one of the remaining sides having an opening there- 100 through, lamps mounted within the casing upon the remaining side, a stencil member having numbers indicated thereby corresponding to the numbers of the license tag and which stencil member is received with- 105 in the open side of the casing, and means to retain the casing in positions in which the standard license tag and the stencil number illuminated by the lamp will be selectively displayed.

2. A combined license display and tail lamp including a substantially triangular casing having bearing trunnions at the ends thereof, bearing brackets in which said casing is mounted to be capable of revoluble 115 movement and said bearing brackets adapted to be mounted upon the rear of the vehicle, one of the sides of the casing being formed to receive a standard license tag and one of the remaining sides having an opening 120 therethrough, lamps mounted within the casing upon the remaining side, a stencil member having numbers indicated thereby corresponding to the numbers of the license tag and which stencil member is received within the open side of the casing, a covering 125 for the stencil member, a colored transparent sheet placed over the stencil mem-

ber to color the light as shown therethrough, a substantially triangular body portion formed in conjunction with one of the trunnions, and a spring carried by the adjacent bracket member to bear against the sides of the body portion thus formed and to retain the casing in adjusted position.

In testimony whereof I affix my signature in presence of two witnesses.

WILLIAM A. REICH.
